(57) CLAIM

The ornamental design for a top cap of cosmetic container, as shown and described.

DESCRIPTION

FIG. 1 is a perspective view of a top cap of cosmetic container showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a reduced scale perspective view showing the design in use with a cosmetic container shown in broken lines; and,

FIG. 9 is a further perspective view showing the design in use with an alternate cosmetic container shown in broken lines.

The broken line showing of the cosmetic containers in FIGS. 8 and 9 is for illustrative purposes only and forms no part of the claimed design.
